UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

HYDROCARBON-OIL CONVERSION

Application filed July 30, 1927. Serial No. 209,629.

The present invention relates to hydrocarbon oil conversion, and refers more particularly to subjecting hydrocarbon oils to atmospheric or substantially atmospheric cracking conditions under cracking or conversion temperature to produce therefrom high yields of useful low boiling point range hydrocarbons suitable for motor fuel and the like.

It is one of the main objects of the present invention to produce a product which possesses high anti-knock properties.

It is another object to produce a distillate which meets the commercial requirements for motor fuel as to initial and end boiling point range, gravity, et cetera, as a direct product of the process, thus eliminating subsequent expensive distillation and refining steps.

It is another object of the invention to carry out an operation wherein hydrocarbon oil is subjected to a conversion temperature while being maintained under substantially atmospheric pressure conditions thereby materially decreasing the cost of apparatus in which the process may be carried out.

A still further object of the invention is to provide a process in which the oil to be treated is adapted to be passed successively through zones wherein it is brought into physical relationship with vapors progressing in an opposite direction whereby efficient scrubbing and fractionation of the vapors and vaporization of the low boiling point fractions of the charging stock takes place, that is, vapors evolved in a preceding zone are caused to pass through pools of liquid of progressively cooler temperature on their way to the condenser and receiver, whereby repeated and prolonged fractionation is permitted, thus condensing substantially all of the undesirable heavy fractions and permitting the production of a final distillate which conforms to all of the commercial requirements for motor fuel.

The unvaporized portions of the charging stock together with the condensed portions of the vapors are passed successively from zone to zone in a direction counter-current to the flow of the vapors, the temperature of which zones progressively increases. The unvaporized hydrocarbons in the last zone are re-

moved and subjected to the action of heat in a furnace whereby they are raised to a desired cracking temperature.

In the preferred embodiment of the invention, the zones through which the charging stock progressively passes to the heating zone, are preferably externally unheated, that is, these zones are not subjected to such heating conditions as would raise the oil passing therethrough to a conversion temperature. While it may be desirable to subject any of said zones to such heating as would maintain the temperature to which the oil was raised in the next preceding zone it is not contemplated that while the oil is passing through these zones it should be raised to such a temperature as would cause conversion.

The utility of the invention, as well as other objects and advantages will be hereinafter more particularly apparent.

The single figure in the drawing is a side elevational diagrammatic view of apparatus in which the invention may be carried out.

Referring more in detail to the drawing, 1 designates a charging stock inlet line in which is interposed a valve (not shown) adapted to be fed by means of pump 2, which draws charging stock from any desired source of supply, such as storage. The charging stock is introduced into one of a series of serially connected chambers 3 wherein the charging stock is brought into physical contact with vapors released from a preceding chamber 4, as will be hereinafter described. The chamber 3 is similar to chambers 4, 5 and 6. Each of the chambers 3, 4, 5 and 6 comprises a metal shell which may be provided with insulation to prevent loss of heat by radiation. The unvaporized portion of the charging stock may be removed from chamber 3 through line 7, and by means of pump 8 may be introduced into the next preceding chamber 4. A by-pass 9, in which is interposed a valve 10, may be provided, by means of which the pump 8 may be by-passed, in which latter event the valves 11 in line 7 are closed.

It is to be noted that the oil removed from the chamber 3 is introduced at a point intermediate the height of the chamber 4, pref-

erably at a point between the top and center. The oil introduced into the chamber 4 is subjected to physical contact with vapors evolved in a preceding chamber in the same manner as the oil introduced to the chamber 3, and is removed through line 7', in which may be interposed a pump 8', and introduced into the chamber 5. A by-pass 9' controlled by valve 10' may be provided whereby the 10 pump 8' may be by-passed, if so desired, in which event the valves 11' are closed. The oil introduced into the chamber 5 will be subjected to similar physical contact with vapors formed in a preceding zone, and the unvaporized portions of the oil from chamber 5 15 may be withdrawn through the line 7", in which may be interposed a pump 8". A by-pass 9", controlled by valve 10", may be provided to by-pass the pump 8", in which 20 event the valves 11" are closed.

The oil discharges from line 7" into the chamber 6. The chamber 6 is the last of the three chamber 4, 5 and 6 through which the charging stock passes. It is understood, of course, that there may be any number of these 25 chambers, from one to ten, more or less, and that the four chambers shown in the drawings are purely illustrative. In addition, any of these chambers 3, 4, 5 and 6 may be 30 by-passed by manipulation of valves and suitable connecting lines (not shown) but obvious to those skilled in this art.

The unvaporized oil from the chamber 6 35 may be withdrawn through either or both of the draw-off lines 12, in which may be interposed a valve 13, which line 12 merges with main line 14, in which may be interposed a pump 15, line 14 communicating with a heating tube 16 which may comprise connected lengths of tubing formed into a coil. A by-pass 17 controlled by valve 18 may be 40 connected into the line 14 whereby the pump 15 may be by-passed, if desired, in which event the valves 19 are closed.

The heating coil 16 may be mounted in any conventional type furnace or heating zone 45 20, which may be heated by means of burner 21. While passing through the heating coil 16 the oil may be raised to the temperature 50 which it has been decided is the desired temperature for most efficient conversion, which temperature will, of course, depend to a great extent upon the character of charging stock 55 being treated and the types of products desired, all of which is within the skill and knowledge of those versed in the art.

The oil after being heated while passing 60 through the coil 16 is transferred through transfer line 22, in which may be interposed a valve 23, discharging into a suitable soaking 65 instrumentality 24, which may comprise a passageway of any form. While I have illustrated in the drawings the element 24 as comprising a chamber, yet it must be understood, of course, that this element may com-

prise a coil of any other suitable instrumentality wherein the temperature of the oil is maintained at substantially the temperature to which it was heated while passing through coil 16 whereby a prolongation of the temperature during which the oil is subjected to the desired conversion temperature is effected. It is obvious, of course, that the element 24 may be entirely dispensed with, particularly if the heating coil 16 is so designed as to permit the oil to be maintained at desired conversion conditions for the length of time which has been found most desirable. If the element 24 is used, all of the products may be withdrawn together through the outlet 25, in which may be interposed a valve 26, being introduced into the chamber 6. An auxiliary safety or gas line 27, in which may be interposed a valve 28, may connect element 24 with chamber 6. When the soaking element 24 takes the form of a coil this line 27 may be dispensed with. Or it may be desirable to discharge all products of conversion from the element 24 through line 25, as shown, connected to the bottom of said element 24. It may also be desirable to separate in element 24 the lighter products of conversion in the form of vapors from heavy portions in the form of liquid, semi-solid or solid form.

If separation is desired in element 24 this element may be provided with a bottom draw-off, as shown at 25' and controlled by valve 26', to permit clean circulation to the balance of this system, while the vaporous products of conversion may be passed from the upper portion of element 24 into chamber 6 through side line 25" controlled by valve 26".

The products of conversion discharged from the soaking element 24 through lines 25 or 25" are passed into the lower portion of the chamber 6 where they come in contact with the oil charged into this chamber 6 through line 7", as heretofore described. This physical contact of this oil with the products of conversion causes preheating of the former and condensation or fractionation of the heavier portions of said products of conversion. These condensed portions are withdrawn through either or both lines 12 and directed to the cracking coil 16, as heretofore described.

The vapors remaining uncondensed in chamber 6 are withdrawn from the top thereof through line 29, on which may be interposed vapor pump or blower 30, controlled by valves 31. A by-pass 32 controlled by valve 33 may be provided around vapor pump 30. The vapors from the top of chamber 6 are thus passed by means of blower or pump 30 or through by-pass 32 into the lower portion of chamber 5. In chamber 5 the vapors come in contact with the oil charged thereto through line 7', causing a reaction in chamber 5, as heretofore described for chamber 6. The va-

5 pores uncondensed pass out through vapor line 29', in which may be interposed a pump 30', controlled by valves 31', which pump may be by-passed by means of the by-pass 32' controlled by valve 33'. Vapors from line 29' discharge into the lower portion of chamber 4 where they come into physical contact with the charging stock introduced through the line 7.

10 The same reaction takes place in the chamber 4 as heretofore described for the chambers 5 and 6, the vapors being removed through vapor outlet line 29'', in which may be interposed a pump or blower 30'', controlled by valves 31'', which pump may be by-passed by means of the by-pass line 32'' controlled by valve 33''. The vapors discharging through the line 29'' may be introduced to the chamber 3 into which the raw 15 charging stock is introduced. Physical commingling takes place in the chamber 3 between the vapors and charging stock, causing condensation of insufficiently converted or heavy fractions of said vapors and heating 20 and perhaps vaporization of some of the lighter fractions of the charging stock. Vapors remaining uncondensed, may be withdrawn from the chamber 3 through the vapor outlet line 34, in which may be interposed 25 a valve 35, being condensed in the condenser coil 36 and collected as liquid distillate in the receiver 37, which may be provided with the liquid draw-off line 38 controlled by valve 39 and with the gas relief pipe 40 controlled 30 by valve 41.

35 It is to be understood, of course, that any suitable finishing liquid may be introduced to the chamber 3 for the purpose of producing a more stable end point product. For 40 instance, controlled quantities of the distillate collected in the receiver 37 may be returned to the upper part of the chamber 3, or a dephlegmator or other suitable instrumentality may be connected into the line 34 between the chamber 3 and condenser 36 for this 45 purpose, in which event the reflux may be returned to any of the chambers 3, 4, 5 and 6 or to the charging line 14.

50 The operation of the apparatus described in the foregoing description should be apparent to those skilled in this art. The unvaporized portion of the charging stock is progressively passed through zones of increasing temperature wherein vapors from 55 preceding zones which are passing in a countercurrent direction to the flow of charging stock are brought into physical contact therewith, thus creating to some extent an equilibrium between vapors and liquid whereby the 60 heavier fractions or insufficiently converted fractions of the vapors will be condensed and subjected to further treatment while the sufficiently converted fractions will be passed 65 successively through the various zones to be

eventually removed through the vapor line 34.

As a feature of the invention, the entire apparatus is adapted to be maintained at atmospheric pressure, that is the pressure imposed by the pumps is only sufficient to overcome fractional resistance and is not intended in any way to impose a superatmospheric pressure on the oil and vapors for the purpose of subjecting same to a cracking temperature under superatmospheric pressure.

70 The vapor pumps 30, 30' and 30'' and only used where it is necessary to impose enough pressure on the vapors to cause them to pass into the succeeding chamber. In addition, the use of the vapor pumps 30, 30' and 30'' assist in removing vapors from the preceding chamber through the vapor lines 29, 29' and 29'', and in addition may accelerate the flow of liquid through the coil 16, pipe 22, element 24, and transfer line 25.

75 As a feature of the present invention, in order to permit operating under the principle of what is termed clean circulation, the heavy residue may be withdrawn through the line 25' controlled by 26', and prevented from again passing through the heating coil or any of the chambers 3, 4, 5 and 6.

80 Each of the chambers 3, 4, 5 and 6 may be provided with liquid draw-off lines 42 controlled by valve 43 through which heavier residue from each chamber may be separately withdrawn. This residue may be cooled and collected separately or may be combined and used for fuel.

85 As an example merely, and without intending to limit the process in any way, the following temperature conditions may be maintained. The oil passing through the heating coil 16 may be raised to a temperature of, say 1000° F., more or less, which may be maintained while passing through the element 24. The temperature conditions maintained in each of the four chambers 6, 5, 4 and 3 may be, respectively 700° F., more or less, 650° F., 90 more or less, 550° F., more or less, and 450° F., 95 more or less.

100 The temperature of the vapors leaving the chamber 3 through the line 34 may be very accurately controlled to comply with end boiling point commercial specifications by introducing any of the usual cooling mediums, such, for instance, as distillate returned from the receiver 37.

105 From the foregoing it will be apparent that the vapors are caused to pass through zones of successively decreasing temperature while the unvaporized liquid is caused to pass through zones of progressively increasing temperatures, while at the same time causing 110 said vapors to be brought into physical contact with the charging stock, preferably by causing the vapors to percolate through bodies of unvaporized charging stock.

115 In some instances it may be desirable to 120

maintain relatively mild conditions of temperature and pressure on the oil passing through the coil 16, which oil would thus be heated to such temperature as would effect conversion of the hydrocarbons without the formation of substantial amounts of solid or semi-solid residue. The conversion effected in this instance, of course, would be limited. In this same operation it may be desirable to limit the soaking time to arrest conversion before substantial amounts of semi-solid or solid residue are formed. Thus, the object of such an operation is to vaporize the oil and effect a partial cracking thereof to separate therefrom, in elements 24, 6, 5, 4 and 3, the heavier fractions which tend to form substantial coke deposits when subjected to additional cracking. Thereby only the lighter partially converted fractions are subjected to additional cracking, which could be done in a superheater.

This superheater may be connected by the lines 44 controlled by valves 45 communicating respectively with the vapor lines 29, 29' and 29'' on one end and on the other with the header 46. The latter communicates with a superheating coil 47 mounted in a furnace illustrated diagrammatically at 48 heated by means of burner 49. The vapors withdrawn from any of the vapor lines 29, 29' or 29'' by obvious manipulation of the valves 45 pass into the header 46 and through the heating coil 47 where said vapors are subjected to conditions of temperature such that substantial conversion into light products possessing anti-knock properties when used as motor fuel will be obtained. The vapors may be raised, for instance, to a temperature of 950 to 1200° F., more or less, and after passing through the superheater they exit through the line 50 with which return branches 51 controlled by valves 52 communicate for returning the heated vapors to a desired vapor line 29, 29' or 29''.

In this manner the formation of heavier residue and solid coke is materially decreased below that which would be the result of cracking effected in a single operation, which would produce an equivalent conversion into light products.

On account of the relatively high temperature of the vapors being introduced to the chambers 5, 4 and 3 some portions of the charging stock may vaporize particularly in chambers 5 and 4. This vaporized portion will be subjected to some cracking in the superheater with the vapors resulting from the primary cracking in coil 16. The superheater is preferably interposed between chambers 6 and 5, although means are provided for superheating the vapors passing between chambers 5 and 4 and 4 and 3 if found desirable. Where the vapors are superheated while passing between chambers 5 and 4 or 4 and 3, it might be well to provide additional

chambers between chamber 3 and condenser 36 to provide for adequate fractionation.

I claim as my invention:

1. In the art of converting high boiling point hydrocarbons to low boiling point hydrocarbons, the process which comprises contacting untreated oil with cracked oil vapors just following the subjection of such vapors to a cracking temperature in the vapor phase, subjecting the untreated oil following contact with said cracked vapors to a mild cracking temperature in a heating zone, delivering the oil following subjection to said mild cracking temperature to a vaporizing zone, removing from said vaporizing zone vapors and liquid oil before the cracking reaction has proceeded to the extent of forming coke, subjecting the vapors following their removal from said vaporizing zone to a cracking temperature while in the vapor phase to supply the cracked oil vapors for contact with the incoming untreated oil.

2. In the art of converting high boiling point hydrocarbons to low boiling point hydrocarbons, the process which comprises contacting untreated oil with cracked oil vapors just following the subjection of such vapors to a cracking temperature in the vapor phase, subjecting the untreated oil following contact with said cracked vapors to a mild cracking temperature in a heating zone, delivering the oil following subjection to said mild cracking temperature to a vaporizing zone, removing from said vaporizing zone vapors and liquid oil before the cracking reaction has proceeded to the extent of forming coke, subjecting the vapors following their removal from said vaporizing zone to a cracking temperature while in the vapor phase to supply the cracked oil vapors for contact with the incoming untreated oil, and effecting the operation of the process under substantially atmospheric pressure.

3. In the art of converting high boiling point hydrocarbons to low boiling point hydrocarbons, the process which comprises contacting untreated oil with cracked oil vapors just following the subjection of such vapors to a cracking temperature in the vapor phase, subjecting the untreated oil following contact with said cracked vapors to a mild cracking temperature in a heating zone, delivering the oil following subjection to said mild cracking temperature to a vaporizing zone, removing from said vaporizing zone vapors and liquid oil before the cracking reaction has proceeded to the extent of forming coke, subjecting the vapors removed from said vaporizing zone to partial fractionation, in then subjecting the partially fractionated vapors to a cracking temperature while in the vapor phase to supply the cracked oil vapors for contact with the untreated oil.

4. In the art of converting high boiling point hydrocarbons to low boiling point

hydrocarbons, the process which comprises contacting untreated oil with cracked oil vapors just following the subjection of such vapors to a cracking temperature in the vapor phase, subjecting the untreated oil following contact with said cracked vapors to a mild cracking temperature in a heating zone, delivering the oil following subjection to said mild cracking temperature to a vaporizing zone, removing from said vaporizing zone vapors and liquid oil before the cracking reaction has proceeded to the extent of forming coke, subjecting the vapors removed from said vaporizing zone to partial fractionation, in then subjecting the partially fractionated vapors to a cracking temperature while in the vapor phase to supply the cracked oil vapors for contact with the untreated oil, and effecting the operation of the process under substantially atmospheric pressure.

5. An oil cracking process which comprises passing charging oil for the process through a series of chambers maintained at progressively increasing temperatures from first to last, removing unvaporized charging oil from the last chamber of the series and passing the same through a heating zone, introducing vapors evolved by the heating to said last chamber to physically contact with liquid oil therein, removing vapors from said last chamber and passing the same through the remaining chambers of the series in a direction opposite to the flow of charging oil through the series of chambers, subjecting vapors from one of said chambers to vapor phase cracking during its flow to the next preceding chamber in the series, and removing and condensing vapors from the first chamber of the series.

40 6. An oil cracking process which comprises passing charging oil for the process through a series of chambers maintained at progressively increasing temperatures from first to last, removing unvaporized charging oil from the last chamber of the series and passing the same through a heating zone, introducing vapors evolved by the heating to said last chamber to physically contact with liquid oil therein, removing vapors from said last chamber and passing the same through the remaining chambers of the series in a direction opposite to the flow of charging oil through the series of chambers, subjecting vapors from each of said chambers but the first to vapor phase cracking during its flow to the next preceding chamber, and removing and condensing vapors from the first chamber of the series as a final product of the process.

7. An oil cracking process which comprises passing charging oil for the process through a series of chambers maintained at progressively increasing temperatures from first to last, removing unvaporized charging oil from the last chamber of the series and passing the same through a heating zone, introducing

vapors evolved by the heating to said last chamber to physically contact with liquid oil therein, removing vapors from said last chamber and subjecting the same to cracking in the vapor phase, passing the cracked vapors resulting from the vapor phase cracking through preceding chambers in the series in a direction opposite to the flow of charging oil therethrough, and removing and condensing vapors from the first chamber of the series as a final product of the process.

In testimony whereof I affix my signature.
